Application July 8, 1936, Serial No. 89,668
In Great Britain July 9, 1935

6 Claims. (Cl. 178—44)

The present invention relates to circuits suitable for use as intervalve couplings and for like purposes.

In thermionic valve amplifiers which are required to provide uniform amplification of electrical variations, such as television picture signals, including components of frequencies within a wide range, it is often found that stray capacities such as the inter-electrode capacities of the amplifier valves cause the response of the amplifier to depart from uniformity at the higher frequencies of the range.

Now in many amplifiers, such as those employed for television purposes, for example, it is often desired that no relative phase displacement of oscillations at different frequencies shall take place; in some cases, however, phase displacement the magnitude of which is proportional to frequency is permissible, since such a displacement is merely an advance or delay of the applied signal as a whole with respect to time, which is of no consequence. In such amplifiers, it is inconvenient to compensate for a falling-off of response at high frequencies by the use of attenuation-correcting means, since such means introduce relative phase shift which is not proportional to frequency, and the correction of such phase shift as a matter of considerable practical difficulty.

It is the object of the present invention to provide a circuit for intervalve coupling and like purposes, by the use of which the difficulties discussed above can be avoided or reduced.

The present invention accordingly provides a four-terminal network suitable for use, for example, as an intervalve coupling, said network having an input shunt capacity and an output shunt capacity which is greater than twice or less than one-half the input shunt capacity, in which two inductance coils are arranged in series between said input and output capacities, and in which a resistance is connected effectively in shunt in said network at the junction of said coils, the inductances of said coils and the magnitude of said resistance being so chosen either that the attenuation introduced by said network is approximately uniform over a substantial range of frequencies, or that, within said range, the phase shift introduced is substantially proportional to frequency. Either or both of the said capacities may be constituted wholly or in part by distributed capacity such as an interelectrode capacity of a thermionic valve, a photoelectric cell, or the like.

The invention further provides a circuit arrangement comprising first and second thermionic

valves, having their cathodes connected together and to the negative terminal of an anode current source, in which two inductance coils are connected in series between the anode of said first valve and the control grid of the second, and in which a resistance is connected between the junction of said coils and the positive terminal of said source, the effective anode-cathode and control grid-cathode capacities of said valves respectively forming with said coils and said resistance a four-terminal network which provides approximately uniform attenuation over a substantial range of frequency, or in which over a substantial range of frequency, the phase shift introduced is substantially proportional to frequency. In a modification the inductances of said coils and the magnitude of said resistance lie between those required to provide substantially uniform attenuation and those which satisfy the requirement that the phase shift introduced shall be proportional to frequency.

In a modification of the invention as set forth in the preceding paragraph, said first valve is replaced by a photoelectric cell.

An embodiment of the invention will now be described, by way of example, with reference to the accompanying drawing.

Referring to the drawing, a screened-grid valve 1 has its cathode connected to earth through a biasing resistance 2 shunted by a by-pass condenser 3, its control grid connected to one of two input terminals 4, and its screen grid connected to a point at a suitable positive potential in a source of space current (not shown), the negative terminal of which is earthed.

The anode of valve 1 is connected through inductance coils L_1 and L_2 , and a coupling condenser 5, all in series, to the control grid of a triode valve 6. The cathode of this valve is earthed through bias resistance 7 and by-pass condenser 8 in shunt, and its anode is connected to a point in the space current source at a suitable positive potential through resistance 9. A grid leak 10 is connected between the grid of valve 6 and earth.

The junction point of coils L_1 and L_2 is connected to a point at a suitable positive potential in the space current source through resistance 11, which serves as the anode resistance of valve 1.

Now the anode-to-screening grid capacity of valve 1 may be represented by a capacity C_1 between anode and earth, since the screening grid is at earthy potential (that is at a potential which is substantially constant relatively to earth).

The control-grid-cathode capacity of valve 6 may be represented by a capacity C_2 connected between the join of coil L_2 and condenser 5, and earth. If it now be assumed that a potential difference is applied to terminals 4 which is of uniform amplitude at all frequencies, the potential difference E set up across capacity C_2 at low frequencies is approximately equal to $i_0 R$, where i_0 is the output current of valve 1, and R is the magnitude of resistance 11. At a frequency ω ,

$$E = \frac{i_0 R}{A}$$

where A is in general a function of ω and is the attenuation of the network constituted by C_1 , C_2 , L_1 , L_2 and resistance 11.

By straightforward analysis, which it is not necessary to set out here, there can be derived an expression for A^2 in terms of ω , C_1 , L_1 , R and the ratios a and b , where

$$a = \frac{C_2}{C_1} \text{ and } b = \frac{L_2}{L_1}$$

this expression containing even powers of ω up to ω^6 . A similar expression can be obtained for

$$\frac{d\phi}{d\omega}$$

ϕ being the phase angle of E with respect to i_0 .

The magnitude R of resistance 11 determines the gain of the valve 1, C_1 is determined mainly by the construction of valve 1, and the values of L_1 , a and b are then chosen, in a manner which will now be outlined, either so as to make A as uniform as possible over a desired frequency range, or to make

$$\frac{d\phi}{d\omega}$$

as constant as possible with frequency over the desired range, or as it is not possible to satisfy completely both these requirements, the invention enables a satisfactory compromise to be achieved.

If in the expression for A^2 mentioned above, the coefficient of ω^2 is equated to zero, the following expression is obtained:

$$L_1 = \frac{C_1 R^2 (1+a)}{2(1+ab)} \quad (i)$$

and equating to zero the coefficient of ω^2 in the expression for

$$\frac{d\phi}{d\omega}$$

gives

$$b = \frac{1-2a}{a(2-a)} \quad (ii)$$

In order to make the phase shift introduced substantially proportional to frequency, a is given a value such that the influence of terms in ω^4 and ω^6 in the expression for

$$\frac{d\phi}{d\omega}$$

is minimised, so that the expression

$$\frac{d\phi}{d\omega} = 1 + k\omega^8$$

is approximately satisfied, where k is a constant. The value for b follows from (ii), and the value for L_1 is obtained by substitution in (i); the design of the circuit is then completely fixed.

In the case of a television amplifier, a convenient value for a is 2.5, that is, $C_2=2.5 C_1$ and C_1 and C_2 are so chosen (for example, by suitable selection of valves) that this condition is sub-

stantially satisfied; when $a=2.5$, it is found that not only is the phase shift introduced substantially proportion to frequency, within a predetermined range of frequency, but that, within that range, the attenuation is approximately uniform. The required value for a can be obtained by augmenting C_1 or C_2 artificially, but if the circuit is required to work up to a very high frequency, such an addition to shunt capacity should preferably be avoided, since the smaller C_1 and C_2 can be made, the higher the frequency up to which the attenuation will be uniform.

In an example, C_1 and C_2 have the values 16 and 40 micro-microfarads respectively, and R is 2000 ohms; in this case, L_1 and L_2 are given the values 45 and 150 micro-henrys respectively.

From an examination of (ii) above, it will be clear that b is positive only when a is greater than 2 or less than one-half, and since

$$b = \frac{L_2}{L_1}$$

it is clear that both coils L_1 and L_2 only have finite positive values when $\frac{1}{2} > a > 2$. In the arrangement described above, $a > 2$; when, however, $a < \frac{1}{2}$, the coils L_1 and L_2 are interchanged in position.

In order to convert the arrangement illustrated in the accompanying drawing into a D. C. amplifier, the condenser 5 may be replaced by a floating battery having its negative terminal connected to the control grid of valve 6, the leak 10 being then omitted. The resistance 11 should preferably be one having a low self-capacity; if desired, however, there may be connected in series between resistance 11 and the join of coils L_1 and L_2 either a coil of an inductance equal to $0.4C_8R^2$, or an inductance of magnitude C_8R^2 shunted by a resistance of magnitude R , C_8 in both cases being the self-capacity of resistance 11; both arrangements provide a measure of compensation for the self-capacity of resistance 11, the compensation provided by the latter method being more complete. If desired, damping resistances may be connected in shunt with coils 45 L_1 and L_2 respectively to prevent amplitude over-swing due to transients; these resistances may have values from 5 to 20 times R , and account must be taken of their presence in designing the circuit by increasing the values of L_1 and L_2 .

The network C_1 , C_2 , L_1 , L_2 , R is of the low-pass filter type. The equivalent band-pass filter can be constructed by connecting condensers in series with coils L_1 and L_2 , and shunting the capacities C_1 and C_2 by inductances; the magnitudes of these additional elements can be determined by an extension of the procedure outlined in the description of the arrangement shown in the accompanying drawing. In the case in which two valves are coupled by a band-pass filter in accordance with this invention, the two valves serving as carrier-frequency amplifiers, the introduction of a certain amount of phase shift may be permissible, and in this case L_1 , and the parameters a and b , are given values such that an expression for the attenuation which is of the following form $a^2=1+K\omega^8$ is obtained, K being a constant. In this way, substantially uniform attenuation, and sharp cut-off is obtained. A similar procedure may be followed in the design of low-pass networks according to the invention for use, for example, as interval coupling circuits for audio-amplifiers, and for other purposes where phase shifts are relatively unimportant, but where uniform attenuation is a desideratum.

Although the invention has been particularly described in its application to intervalve coupling circuits, it can clearly be applied for many other purposes; for example, a network according to 5 the invention can be employed for coupling a photo-electric cell to a thermionic valve. Many further modifications and applications of the invention, within the scope of the appended claims, will occur to those versed in the art.

10 We claim:

1. An electrical network comprising in combination input and output means, said means having shunt capacity, said shunt capacity of said output means being greater than twice said shunt

15 capacity of said input means, inductance coils arranged in series between said input and said output shunt capacities, a resistance connected effectively in shunt in said network at a junction between said inductance coils, the inductance

20 values of said inductance coils and the value of said resistance being chosen so that the attenuation introduced by said network is approximately uniform over a substantial range of frequencies.

2. An electrical network comprising in combi-

25 nation input and output means, said means having shunt capacity, said shunt capacity of said output means being less than one half said shunt capacity of said input means, inductance coils ar-

30 ranged in series between said input and said out- put shunt capacities, a resistance connected effec-

tively in shunt in said network at a junction be- tween said inductance coils, the inductance values of said inductance coils and the value of said

35 resistance being chosen so that the attenuation introduced by said network is approximately uni-

form over a substantial range of frequencies.

3. An electrical network comprising in combi- nation input and output means, said means having shunt capacity, said shunt capacity of said

40 output means being greater than twice said shunt capacity of said input means, inductance coils arranged in series between said input and said output shunt capacities, a resistance connected effectively in shunt in said network at a junc-

45 tion between said inductance coils, the inductance values of said inductance coils and the value of said resistance being chosen so that over a sub-

stantial range of frequencies, the phase shift in-

50 troduced is substantially proportional to fre-

quency.

4. An electrical network comprising in combi- nation input and output means, said means hav- ing shunt capacity, said shunt capacity of said output means being less than one half said shunt capacity of said input means, inductance coils 5 arranged in series between said input and said output shunt capacities, a resistance connected effectively in shunt in said network at a junction between said inductance coils, the inductance values of said inductance coils and the value of 10 said resistance being chosen so that over a sub- stantial range of frequencies, the phase shift in- troduced is substantially proportional to fre- quency.

5. An electrical network comprising in combi- nation input and output means, said means hav- ing shunt capacity, said shunt capacity of said output means being greater than twice said shunt capacity of said input means, inductance coils 15 arranged in series between said input and said output shunt capacities, a resistance connected effectively in shunt in said network at a junction between said inductance coils, the inductance values of said inductance coils and the value of 20 said resistance being chosen so that a compromis- 25 e is effected between causing the attenuation intro- duced by said network to be approximately uni- form over a substantial range of frequencies and causing the phase shift introduced to be substan- tially proportional to frequency over said range 30 of frequencies.

6. An electrical network comprising in combi- nation input and output means, said means hav- ing shunt capacity, said shunt capacity of said output means being less than one half said shunt 35 capacity of said input means, inductance coils arranged in series between said input and said output shunt capacities, a resistance connected effectively in shunt in said network at a junction between said inductance coils, the inductance 40 values of said inductance coils and the value of said resistance being chosen so that a compromis- e is effected between causing the attenuation intro- duced by said network to be approximately uni- form over a substantial range of frequencies and 45 causing the phase shift introduced to be substan- tially proportional to frequency over said range of frequencies.

JOHN HARDWICK.
